Primary Examiner — Melanie Pellegrini

(57) **CLAIM**

The ornamental design for a pair of earrings as shown and described.

DESCRIPTION

1. Pair of earrings

1.1 : Perspective

1.2 : Perspective

1.3 : Front

1.4 : Back

1.5 : Top

1.6 : Bottom

1.7 : Left

1.8 : Right

The design consists of a pair of circle-shaped earrings featuring vertical rows of cubes and diamonds set into the outer part of the earrings; all the angles on the sides of the faces of the cubes are cut at 45 degrees.

1 Claim, 8 Drawing Sheets
